UNITED STATES PATENT OFFICE.

HENRY L. LEIBE, OF NEWARK, NEW JERSEY.

DESIGN FOR A MATCH OR ASH RECEIVER.

SPECIFICATION forming part of Design No. 20,532, dated February 24, 1891.

Application filed January 20, 1891. Serial No. 378,478. Term of patent 3½ years.

To all whom it may concern:

Be it known that I, HENRY L. LEIBE, a citizen of the United States, residing at Newark, in the county of Essex and State of New Jersey, have invented and produced a new and original Design for a Match or Ash Receiver; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

15 The accompanying photograph shows the newly-designed match, ash, or salt receiver with sufficient clearness to illustrate my design.

The leading feature of the design consists 20 in the ash or match receiver shaped like or having the configuration of two bivalvular mollusk-shells placed back to back, so that their concavities face oppositely, parts of the surface being covered and parts disclosing 25 the natural design and configurations of coloring.

In said photograph, *a* is the upturned shell-like part, and *b* the base shell-like part. *c* is the exposed or uncovered concave surface of said upturned part, and *d* is a bead-like marginal rim which conceals the natural edge of the shell-like part from view. *e* is a deposit of covering-matter on the outer parts, and *f* are openings in said covering, through which the shell-like parts and the configurations of 35 coloring thereof are seen.

What I claim is—

The design for a match or ash receiver herein shown and described, consisting of the bivalvular mollusk-shell-shaped parts *a* *b*, the 40 outer parts *e* of which are covered and concealed from view and the concaved upper part *c* of which is uncovered and discloses to view the natural configurations of a shell, as set forth.

In testimony that I claim the foregoing I have hereunto set my hand this 10th day of January, 1891.

HENRY L. LEIBE.
